UNITED STATES PATENT OFFICE.

ERASTUS E. WINKLEY AND BENJAMIN PHILLIPS, OF LYNN, MASSACHUSETTS.

EDGE-SETTING MACHINE.

1,034,851.

Specification of Letters Patent.

Patented Aug. 6, 1912.

Application filed December 10, 1906. Serial No. 347,046.

To all whom it may concern:

Be it known that we, ERASTUS E. WINKLEY and BENJAMIN PHILLIPS, citizens of the United States, residing at Lynn, in the 5 county of Essex and State of Massachusetts, have invented certain new and useful Improvements in Edge-Setting Machines; and we do hereby declare the following to be a full, clear, and exact description of the invention, such as will enable others skilled in 10 the art to which it appertains to make and use the same.

The invention relates to machines for setting or burnishing the edges of the soles of 15 boots or shoes, and its object is to provide a machine which will enable the soles of boots or shoes to be rapidly and uniformly set or burnished without requiring any particular skill or care on the part of the operator.

20 To this end one feature of the invention contemplates the provision in a machine provided with a shoe supporting jack of a plurality of edge setting devices the points of operation of which are transferred along 25 different parts of the sole edge by a relative movement of the jack and setting devices while rapid relative movements are being imparted to the jack and setting devices to effectively rub or burnish the edge as the 30 point of operation is transferred along the sole. The burnishing movements of the setting devices with relation to the sole edge secure a rapid and uniform finishing of the edge at the point of operation, while the 35 provision of a plurality of such rapidly operating edge setting devices for operating upon different parts of the shoe enables the burnishing of the sole edge to be quickly completed.

40 It is usual in the manufacture of boots and shoes, and especially of the better grades, to give the sole edge a different shape along the shank from that given to the sole edge around the forepart of the shoe. 45 The burnishing or setting of the sole edges of such shoes therefore requires the use of differently shaped setting devices in operating upon the differently shaped parts of the sole edge.

50 Accordingly a further feature of the invention contemplates the provision in a machine in which relative burnishing movements and relative movements to transfer the point of operation along the sole edge, are imparted to a 55 shoe supporting jack and edge setting devices, of edge setting devices having sole engaging

faces of different forms for operating upon different parts of the sole edge. It is not material to this feature of the invention, broadly considered, whether the differently 60 shaped faces of the setting devices act upon the different parts of the sole edge simultaneously or successively. In the preferred embodiment of the invention, however, the differently shaped faces of the setting devices act successively on the different parts of the shoe sole, and means are provided for shifting the edge setting devices to bring the differently shaped faces into operation successively as the point of operation is transferred along the shoe sole. The provision of 70 edge setting devices having differently shaped edge engaging faces which are successively brought into operation during the transfer of the point of operation along the 75 sole of the shoe supported upon the shoe supporting jack, constitutes another feature of the invention.

The invention also contemplates the provision of different setting tools for operating 80 upon the sole edge on opposite sides of the shoe, and of a separate edge setting tool for operating upon the sole edge at the toe of the shoe, and the invention also contemplates the provision of separate jacks and 85 edge setting devices for right and for left shoes.

Other features of the invention will be noted in connection with the description of the illustrated embodiment thereof. 90

In the drawings Figure 1 is a side elevation of an edge-setting machine embodying the present invention; Fig. 2 is a plan view of the machine; Fig. 3 is a rear elevation; Fig. 4 is a side elevation showing in detail 95 one of the jacks and the mechanism for actuating the shank and forepart tools; Figs. 5 and 6 are respectively a plan view, and a front elevation partly in section, showing in detail a portion of the mechanism for actuating the shank and forepart tools; Fig. 7 is a plan view showing in detail the edge-setting tools and portions of their actuating mechanism; Figs. 8 and 9 are respectively a side elevation and a rear elevation of the 105 mechanism for actuating the toe tool.

The illustrated embodiment of the invention is a duplex machine being provided with two jacks and two sets of edge-setting tools, and being adjusted to operate upon 110 right-hand shoes upon one jack and left-hand shoes upon the other. The jacks are

similar in construction. As shown particularly in Fig. 4, each jack comprises a heel post 1, upon the upper end of which is pivoted a heel pin 2, which enters a socket in the last and is pressed forward by a spring plunger 3 so as to tilt the shoe against the toe support. The heel post slides vertically in a sleeve 4 fixed to a slide 5 mounted upon horizontal ways 6 upon the bed plate 7 of the jack. The slide 5 may be moved horizontally on the ways 6 to accommodate the jack to shoes of different lengths, and by means of a hand screw 8 it is fixed in adjusted position. The toe post 9 carries at its upper end the toe support 10, which is provided with circular curved ribs 11 loosely engaging corresponding grooves in the upper end of the toe post to permit a rocking motion of the toe support to accommodate it to toes of different forms. The toe post slides vertically in a sleeve 12 mounted upon the bed plate 7. The lower ends of the heel and toe posts rest upon a compensating lever 13 by means of which they may be raised so as to press the shoe upward against the fixed heel and toe rests 14 and 15. The heel rest 14 is provided with a rocking arrangement 16 like that of the toe support, and is mounted upon an arm 17 projecting from the frame of the machine. The toe rest 15 is similarly mounted upon an arm 18. The compensating lever (see Fig. 1) is mounted upon the upper end of a rod 20, slidably mounted in the frame of the machine, and the lower end of the rod 20 is embraced by a sleeve at the upper end of a link 21 pivoted at its lower end to a treadle lever 22. A sliding collar 23 on the rod 20 engages the lower end of a compression spring 24 which bears at its upper end against a collar fixed on the rod 20. A catch 25 is pivoted upon the frame of the machine in position to engage and retain the collar 23 when it is moved upward to compress the spring 24, and a hand lever 26 is connected with the catch to release it when necessary.

To insert and secure a shoe on the jack the bed plate 7 is drawn toward the operator 50 along horizontal ways on a bracket 19 projecting from the frame of the machine, and the lasted shoe is then placed upon the heel post. The bed plate of the jack is then pushed back until the toe is in position under 55 the toe rest and the operator then depresses the treadle, thereby compressing the spring 24 which operates through the rod 20 and compensating lever 13 to raise the heel and toe post and press the shoe upward against the heel and toe rests. The catch 25 engages 60 the collar 23 and maintains the jack in this condition until released by the hand-lever 26.

In connection with each jack there are provided edge-setting tools of three kinds, 65 the shank tools for burnishing the sole edge

from the heel to the juncture of the shank and the forepart, the forepart tools for burnishing the sole edge from the latter point to the toe, and the toe tool for burnishing the forward extremity of the sole 70 edge. The shank and forepart tools are mounted upon heads 27 (see Figs. 4 and 7) fixed to the forward ends of shafts 28 journaled in sleeves 29. The rear extremities of the sleeves 29 are provided with forks 30 pivoted in uprights 32 (see Figs. 4, 5 and 6) upon sleeves 33 rotatably mounted in sleeves 34 projecting downward from slides 35. The slides are provided with flanges 36 engaging corresponding ways on the frame 80 of the machine, so that they may be moved longitudinally with respect to the shoe to transfer the point of operation of the edge setting tools along the sides of the shoe. The pivotal mounting of the sleeves 29 permits the tools to rise and fall in accordance with the contour of the sole edge as the tools are moved longitudinally with respect to the shoe. To maintain the tools in contact with the sole edge each sleeve 33 is provided with an arm 37 to which is connected one end of a spring 38, the other end being fixed to the slide 35. This spring tends constantly to swing the sleeve 29 in a direction to press the tool against the sole edge. 90

The burnishing tools are given a constant vibration along the sole edge of slight amplitude to facilitate the burnishing operation. For this purpose the rear ends of the shafts 28 are connected by universal joints 100 40 with links 41 pivotally connected with eccentric straps 42 engaging eccentrics 43 on shafts 44, journaled in uprights 45 on the slides 35 and provided with suitable driving pulleys 46. This arrangement is such that a 105 constant and rapid vibration may be imparted to each tool without interference with its several other movements. 95

In order that the operation may proceed from the heel to the toe of the shoe it is 110 necessary to impart to the tools, in addition to their vibrating movement above described, a general movement longitudinally with respect to the shoe, and for this purpose the slides 35 are moved horizontally in the 115 frame of the machine. As shown in Fig. 4, the slide of the right-hand last is connected by means of a short link 47 with the upper end of a lever 48 fixed (as shown in Fig. 1) upon a rock shaft 49 journaled in 120 the frame of the machine. This rock shaft lever is actuated by a cam 50 on the cam shaft 51 of the machine through suitable connections to be described later.

As shoes are usually finished with edges 125 of different form in the shank and in the forepart, it is necessary, after the edge has been burnished from the heel to the forepart, to substitute a different tool to operate upon the forepart, and the present machine 130

is provided with shank tools 52 and forepart tools 53. These tools are mounted upon a short shaft 39 loosely journaled in the head 27, so that the tools may turn to 5 accommodate themselves to the inclination on the sole edge, and means are provided for automatically substituting the forepart tool for the shank tool at the proper time in the operation of the machine by imparting a 10 half rotation to each of the shafts 28. For this purpose each shaft is provided with a gear wheel 54 located at the rear extremity of the sleeve 29 and splined to the shaft 28. This gear engages a toothed sector on a 15 bell-crank lever 55 pivoted at 56 in the sleeve 33 and having a lateral arm connected by means of a link 57 with a lateral projection from a sleeve 58. The sleeve 58 slides vertically upon a rod 59 fixed at its upper 20 end to the sleeve 33. The lower end of the sleeve 58 is grooved, and is engaged by the forked end 62 of a bell-crank lever journaled at 63 on a bracket 64 mounted on the slide 35. The bell-crank lever carries a cam 25 roll 65 engaging a cam path 66 in a cam disk 67. The cam is mounted upon and splined to a cam shaft 68 passing loosely through the bracket 64 but fixed against longitudinal movement at its rear end, (see Fig. 1) where 30 it is journaled in the frame of the machine. In order that the forepart tool may be substituted in this manner for the shank tool it is necessary to swing the latter out of engagement with the sole edge, which is accomplished by turning the sleeve 33 slightly 35 in the slide 35, and for this purpose the arm 37 is provided with a cam roll 69 engaging a cam path 70 (see Fig. 4) in the cam 67. It is also necessary before swinging the 40 shank tool out of engagement with the sole edge to lock the sleeve 29 in its vertical position with respect to its pivotal connection with the uprights 32, in order that the forepart tool when substituted for the shank 45 tool may occupy the same vertical position as was occupied by the shank tool, corresponding to the height of the sole edge at the point of change. To this end the rock shaft 31 (see Fig. 6) upon which the fork 50 30 is mounted, is keyed to the fork, and upon its outer end is fixed a depending arm 72 carrying a curved friction surface 73 in position to be engaged by a corresponding brake shoe 74. The brake shoe is mounted 55 upon a horizontal lever 75 pivoted to the upright 32 at its outer end and connected at its inner end with a link 76 bearing upon a lever 77 pivoted upon the bracket 64 and carrying a cam roll engaging a cam path 78 60 in the cam 67.

The operation of the mechanism just described is such that when a partial rotation in the direction of the arrow, Fig. 6, is imparted to the cam 67 by the rotation of the 65 cam shaft 68, the sleeve 29 is first locked in

its vertical position, then swung outwardly from the shoe to remove the shank tool therefrom and then a half rotation is imparted to the shaft 28 to reverse the positions of the tools. The sleeve 29 is then allowed to swing inward again until the forepart tool engages the sole edge and the brake shoe 74 then disengages the friction surface 73. After the edge-setting operation has proceeded from the heel to the toe, 70 a partial reverse movement of the cam 67 takes place, thereby substituting the shank tool for the forepart tool in readiness for the operation upon another shoe. But the cam dwells in such position as to leave the 75 shank tool out of contact with the sole edge and fixed in its vertical position, to permit the finished shoe to be removed and a new one to be inserted. After the machine is 80 again set in operation, the cam 67 at once 85 completes its return rotation to the position of Fig. 6, to permit the shank tool to engage the sole edge.

The mechanisms above described are repeated for each pair of tools, there being 90 four such pairs in the duplex machine, and the four cam shafts 68 are connected to operate in unison by means of beveled pinions 80 at their rear ends engaging pinions, 81 on a transverse rock shaft 82 journaled 95 in the frame of the machine. To actuate these shafts at the proper time one of the shafts (see Fig. 2) is provided with a pinion 83 engaging a segment 84 on a bell-crank lever 85 journaled on the frame of the 100 machine and provided with a depending arm 86 carrying a cam roll engaging a cam 87 on the cam shaft 51.

The outer edges of the left-hand shoes and the right-hand shoes are similar in character, so that the slides 35 corresponding to these parts may be moved in unison, and for this reason the slide corresponding to the outer side of the left-hand jack is actuated 105 by a lever 88 fixed to the rock shaft 49 and moving in unison with the lever 48. The inner edges of the two soles are also similar to each other but not to the outer edges, and therefore a single mechanism is used to actuate the slides corresponding to these edges, 110 this mechanism operating, however, differently in point of time from the other slide-actuating mechanism, as will be described.

As has been shown, the tool-changing mechanism operates at a fixed time in the 115 cycle of operations of the machine for both jacks and for both the inside and outside edges of the shoes, but, as is shown in Fig. 7, it is necessary that at such time the inside tools shall have advanced farther toward the 120 toes than the outside tools, owing to the greater length of the inside of the shank, so that it is necessary to provide means for varying the longitudinal movement of the 125 several tools during the operation of the 130

portion previous to the changing of the tools. Furthermore, in operating upon different styles of shoes it is necessary to make further adjustments, as the relative lengths 5 of the shanks and foreparts differ in different styles. For these reasons the lever 48 is connected with its actuating cam 50 through an adjusting mechanism. The lever is provided with a curved slot 90 engaged by a slide 10 block 91 which may be fixed in adjusted position therein. A link 92 is pivoted to the block 91 and at its rear end is connected with a bell-crank lever 93 pivoted at 94 upon an arm 95 loosely journaled upon a shaft 15 109 fixed in the frame of the machine and carrying a roll engaging the cam path 98 in the cam 50. At the upper end 100 of the arm 95 is pivoted a curved arm 99 provided with a T-slot engaged by a slide block 101 20 which may be fixed in adjusted position therein. A link 102 connects this slide block with a lateral arm 103 on the bell crank lever 93. A pin 104 projecting laterally from the forward end of the arm 99 engages a 25 curved slot in a cam plate 105 fixed to the frame of the machine. It will be seen that when the arm 95 moves rearwardly under the influence of the cam path 98 in the cam 50 it carries the arm 99 with it. The bell 30 crank lever 93 tends to rotate to the left and leave the lever 48 unmoved, but this tendency is resisted by the link 102 and the arm 99, and the latter is prevented from swinging upward by its connection with the cam 35 plate 105, and thus when the arm 95 swings back the arm 48 is also swung back, with a motion modified in accordance with the form of the cam plate 105, acting through the connections described. The cam plate is 40 provided with a slot having two portions 106 and 107, the portion 106 being traversed by the pin 104 prior to the exchanging of the shank and forepart tools, while the portion 107 is traversed thereafter. The shape 45 of the portion 107 is such that it causes no movement of the arm 99 with respect to the arm 95, and the arm 99 is so curved with respect to the link 102 in the bell crank lever that whatever the adjustment of the slide 50 block 101 may be, the movement of the lever 48 is not affected by this mechanism after the tools have been exchanged. The portion 106 of the cam path does, however, modify 55 the movement of the lever 48. By moving the slide block 101 in the arm 99 the extent of this modification may be adjusted, and in this way the mechanism may be so arranged that within certain limits of variation the shank tool may be adjusted to attain any desired 60 position upon the sole edge at the time of exchange of the tools.

The curved slot 90 and the slide block 91 afford provision for varying the amplitude of movement as a whole of the lever 48, to

adjust the machine for shoes of different 65 lengths.

The longitudinal movements of the inside tools are effected through a lever 110 loosely journaled on rock shaft 49 and actuated, through adjusting mechanism similar to that 70 above described, by means of a cam path in the cam 87, and this arrangement permits of the independent adjustment necessary, as above pointed out, owing to the difference 75 between the inside and outside edges of the soles.

The cam shaft 51 is set in motion automatically by the depression of the treadle by which the shoe is fixed in position on the jack. A worm-wheel 124 fixed to the cam 80 shaft engages a worm 114 on a shaft 115 driven by a pulley 116 loosely journaled thereon. A clutch 117 operates to connect or disconnect the pulley and the shaft, and is thrown into or out of operation by a rod 85 118 sliding longitudinally and provided with a bell-crank lever 126. A spring 119 engages the bell crank lever and one of the brackets 120 in which the rod 118 slides, and tends normally to move the rod to the left 90 (Fig. 1) to throw the clutch into engagement. This is prevented, however, while the machine is out of operation by a lug 123 fixed to the worm-wheel 124 and engaging the upright arm 122 of the bell crank lever 95 126, thereby holding the lever and the rod 118 to the right. The horizontal arm of the bell-crank lever is connected by a link 127 with an arm 128 fixed to a rock shaft 129 carrying another arm 112 pivoted to the 100 link 21. When the treadle is depressed the arm 112, shaft 129 and arm 128 operate, through the link 127, to rock the bell-crank lever so that its upright arm 122 is disengaged from the lug 123. The spring 119 105 then operates to throw the clutch into engagement and the rotation of the worm-wheel commences in the direction of the arrow, Fig. 1.

The forward extremity or toe of the sole 110 is operated upon by a separate tool 131 (Fig. 8). The toe tool has a rocking connection 132 with a depending arm 133 pivoted at 134 in a yoke 135. The yoke 135 has horizontal arms 136 and 137 loosely journaled upon a vertical shaft 138. The shaft 138 is journaled in the arm 18 and an arm 139 on the frame of the machine. The toe tool has rapid oscillations of small amplitude imparted to it by means of connections 120 comprising a link 140 connecting the yoke 135 with a bell-crank lever 141, pivoted at 142 in a yoke having horizontal arms 143 pivoted upon the shaft 138. The bell crank-lever 141 is pivoted at 145 to an eccentric 125 strap 146 engaging an eccentric on the shaft 138. A pulley 148 fixed on the shaft rotates it constantly at high speed, thereby actuat-

- ing an eccentric, and, through the connections above described, imparting a rapid vibration to the toe tool. In addition to this vibration it is necessary to swing the yoke 5 135 through a considerable arc to cause the toe tool to work all around the toe, and for this purpose a gear segment 150 is fixed to the arm 143 and engages a rack bar 151 sliding horizontally in the frame of the machine. 10 The rack bar (see Fig. 2) engages a gear segment 152 on a lever 153 pivoted in the frame of the machine, and provided with a cam roll engaging a cam path in a cam 154 mounted on a shaft 155 journaled on the 15 frame of the machine. The shaft 155 is connected by a sprocket chain 156 with the cam shaft 51 so as to rotate in unison therewith. The cam path is so formed that the toe tools, starting from their left-hand position, 20 as shown in Fig. 2, are swung to a corresponding right-hand position while the shank and forepart tools are advancing toward the toe, so that the toe is burnished or set at the same time as the side edges of the 25 sole. During its operation the toe tool is held in contact with the sole edge by means of a spring 157 engaging the arm 133 and a rod 158 passing loosely therethrough and fixed in a depending lug on the arm 137. 30 It is necessary to remove the toe tool from the sole edge before the forepart tools reach the toe, to afford room for the latter to operate, and for this purpose each of the depending arms 133 is provided with a horizontal arm 159 in position to be engaged by the curved extremity 160 of a lever 161 fixed to a rock shaft 162 journaled in the frame of the machine. The rock shaft 162 has an arm 163 provided with a cam roll engaging 40 a cam path 164 in the cam 154 (see Figs. 1 and 2). At the proper time in the operation of the machine the arc-shaped members 160 are raised, thereby engaging and lifting the arms 159 and swinging the toe tools away 45 from the sole. This position is maintained by the toe tools until another shoe is inserted in the machine and its operation is resumed. 50 The machine above described is capable of operating upon shoes of all sizes and styles with slight adjustments which may be readily made by the operator, and by the use of shank tools and forepart tools, with automatic means for exchanging them at 55 the proper time in the operation of the machine, the machine is adapted to produce exact equivalents of the results produced at present by manual operations without the loss of time incident to transferring the 60 work from one tool to another. Owing to the fact that the sole is operated upon at three points at the same time, the operation of the machine is very expeditious, and its speed is limited practically to the capacity of the operator to remove and replace the 65 work.
- While the invention has been illustrated and described as embodied in a machine for setting the edges of shoes, it will be understood that certain features of the invention 70 are not confined in their application to machines for performing this operation, but may be embodied in machines for performing other or various operations on a shoe. The invention is not limited to the details 75 of construction and operation of the illustrated embodiment, but may be embodied in other forms broadly defined in the claims.
- Having now described the invention, 80 what is claimed is:
1. An edge-setting machine having, in combination, a shoe-supporting jack, a plurality of edge-setting tools engaging opposite sides of the sole-edge of the shoe on the jack and having a rapid vibrating movement of slight amplitude along the sole edge, and means for imparting comparatively slow relative movements of greater amplitude to the jack and the tools to transfer the point of operation of the tools along 85 the sole edge, substantially as described. 90
2. An edge setting machine, having, in combination, a shoe supporting jack, a forepart tool for operating on the forepart of the sole edge, a shank-tool for operating on the shank of the sole edge, means for relatively moving the jack and tools to transfer the point of operation of the tools along the sole edge, and means for imparting burnishing movements to the tools as the 95 point of operation is transferred along the sole edge, substantially as described. 100
3. An edge-setting machine having, in combination, a shoe-supporting jack, a plurality of edge-setting tools arranged on opposite sides of the sole edge, and means for imparting to said parts relative movement to transfer the point of operation along the sole edge, and a distinctive burnishing movement, substantially as described. 105
4. An edge-setting machine having, in combination, a shoe-supporting jack, a plurality of edge-setting tools of different forms engaging different parts of the sole edge, and means for imparting burnishing movements to the tools and means for imparting additional relative movements to the jack and tools to transfer the point of operation of the tools along the sole edge, substantially as described. 110
5. An edge-setting machine having, in combination, a shoe-supporting jack, a shank tool engaging the shank of the sole edge, a fore-part tool engaging the forepart of the sole edge, and means for imparting burnishing movements to the tools and means for imparting additional relative movements to the jack and tools to transfer the 115
- 120
- 125

- point of operation of the tools along the sole edge, substantially as described.
6. An edge-setting machine having, in combination, a shoe-supporting jack, a plurality of edge-setting tools, means for changing the relative longitudinal position of the jack and tools, and means for bringing the tools into operation successively, substantially as described.
10. 7. An edge-setting machine having, in combination, a shoe-supporting jack, a fore-part tool, a shank tool, means for actuating the tools, and means for throwing one tool into operation and the other tool out of operation during the continued operation of the machine, substantially as described.
15. 8. An edge-setting machine having, in combination, a shoe-supporting jack, a fore-part tool, a shank tool, means for imparting burnishing movements to the tools, means for imparting relative movements to the jack and the tools to transfer the point of operation along the sole edge, and means acting automatically to throw one of said tools out of, and the other into, operation at the juncture between the shank and the forepart, substantially as described.
20. 9. An edge-setting machine having, in combination, a shoe-supporting jack, a tool having a movement along the lateral edge of the forepart of the sole, an independent tool having a movement around the toe, and means for actuating the tools, substantially as described.
25. 10. An edge-setting machine having, in combination, a shoe-supporting jack, and a plurality of tools engaging and operating on both lateral edges of the shoe sole simultaneously, means for imparting burnishing movements to the tools and means for imparting additional relative movements to the jack and tools to transfer the point of operation of the tools along the sole edge, substantially as described.
30. 11. An edge-setting machine having, in combination, a shoe-supporting jack, a shank tool and a fore-part tool for operating on the right hand edge of the shoe sole, a shank tool and a forepart tool for operating on the left-hand edge of the shoe sole, means for imparting relative movements to the jack and the tools to transfer the point of operation along the sole edge, and means for automatically throwing one set of the tools out of operation and the other set of the tools into operation, when the juncture between the shank and the forepart is reached, said means operating to so shift the tools at different points on the opposite sides of the shoe according to the difference in length between the inside and the outside of the shank, substantially as described.
35. 12. An edge-setting machine having, in combination, a shoe-supporting jack, a shank tool and a fore-part tool for the point of operation of the tools along the sole edge, substantially as described.

right-hand edge of the sole, a shank tool and a fore-part tool for the left-hand edge of the sole, means for shifting the points of operation along the sole on opposite edges simultaneously in the same direction but at different speeds so that the juncture between the shank and the forepart shall be reached by the tools on both sides simultaneously, and means operating automatically, when this point is reached, to substitute one of the tools for the other on both sides of the shoe, substantially as described.

13. An edge-setting machine having, in combination, a shoe-supporting jack, a plurality of edge setting tools including a tool for operating on the toe of the sole, and means for imparting to said tool and jack relative oscillations of comparatively great amplitude to transfer the point of operation around the toe, and relatively short and rapid oscillations to cause the tool to burnish the sole edge, substantially as described.

14. An edge-setting machine having, in combination, a shoe-supporting jack, tools for operating on the lateral edges of the shoe sole, means for moving the jack and the tools relatively to transfer the point of operation toward the toe, a tool for operating on the toe, and means for moving it out of operative position as the first-mentioned tools approach the toe, substantially as described.

15. An edge-setting machine having, in combination, two jacks for supporting a right-hand shoe and a left-hand shoe respectively, tools for operating on both lateral edges of both shoe soles simultaneously, mechanism operating simultaneously on the tools engaging two of the homologous edges of the soles to transfer the points of operation of such tools along the sole edges, and independent mechanism acting simultaneously on the other tools, substantially as described.

16. An edge setting machine, having, in combination, a shoe supporting jack and a plurality of edge setting tools for operating on opposite sides of the sole edge relatively movable to transfer the point of operation of the tools along the sole edge, and mechanism for imparting rapid vibratory movements to the setting tools as the point of operation is transferred along the sole, substantially as described.

17. An edge setting machine, having, in combination, a shoe supporting jack, fore-part and shank tools for engaging respectively the forepart and shank of the sole edge, mechanism for relatively actuating the jack and tools to transfer the point of operation along the sole edge and to give the tools a rapid burnishing movement as the point of operation is transferred along the sole edge, substantially as described.

18. An edge setting machine, having, in combination, a shoe supporting jack, edge setting devices having differently shaped edge engaging faces for operating on different parts of the sole edge, mechanism for relatively actuating the jack and setting devices to transfer the point of operation of the edge setting devices along the edge of the sole, and to give the edge setting devices rapid burnishing movements relative to the sole as the point of operation is transferred along the sole, substantially as described. 5
19. An edge setting machine, having, in combination, a shoe supporting jack, edge setting devices having differently shaped edge engaging faces for operating on different parts of the sole edge, mechanism for relatively actuating the jack and edge setting devices to transfer the point of operation of the edge setting devices along the edge of the sole and to give the edge setting devices rapid burnishing movements relative to the sole as the point of operation is transferred along the sole, and mechanism 10 acting automatically to shift the edge setting devices to bring into operation the edge engaging face corresponding to the part of the sole being operated upon, substantially as described. 15
20. An edge setting machine, having, in combination, a shoe supporting jack and a plurality of edge setting tools for operating on different parts of the sole edge relatively movable to transfer the point of operation along the sole edge, and means for bringing the tools into operation successively as the point of operation is transferred along the sole, substantially as described. 20
21. An edge setting machine, having, in combination, a shoe supporting jack, edge setting devices having differently shaped edge engaging faces for operating on different parts of the sole edge, mechanism for relatively actuating the jack and edge setting devices to transfer the point of operation of the edge setting devices along the edge of the sole, and mechanism acting automatically to shift the edge setting devices to bring into operation the edge engaging face corresponding to the part of the sole being operated upon, adjustable to vary the point at which the edge setting devices are shifted for different styles of 25 shoes, substantially as described. 25
22. An edge setting machine, having, in combination, a shoe supporting jack, edge setting devices having differently shaped edge engaging faces for operating on the shank and forepart of the sole edge, mechanism for relatively actuating the jack and edge setting devices to transfer the point of operation of the edge setting devices along the edge of the sole, and mechanism acting 30 automatically at the juncture of the fore- 60
- part and shank to change the edge engaging face adjustably for different styles of shoes, substantially as described. 65
23. An edge setting machine, having, in combination, a shoe supporting jack and a plurality of tools engaging and operating on each lateral edge of the shoe sole, means for imparting burnishing movements to the tools, and means for imparting additional relative movements to the jack and tools to transfer the point of operation along the sole edge, substantially as described. 70 75
24. An edge setting machine, having, in combination, a shoe supporting jack and a plurality of edge setting tools for operating on different parts of the same lateral sole edge relatively movable to transfer the point of operation of the tools along the sole edge, and mechanism for imparting rapid vibratory movements to the setting tools as the point of operation is transferred along the sole, substantially as described. 80 85
25. A machine for operating on shoes, having, in combination, a tool, a shoe support, mechanism for causing the point of operation to be transferred along the margin of the shoe sole, and mechanism operating automatically to interrupt the operative engagement of the tool with the shoe when the tool arrives at a predetermined point on said margin, substantially as described. 90 95
26. A machine for operating on shoes, having, in combination, a tool, a shoe support, mechanism for causing the point of operation to be transferred along the margin of the shoe sole, mechanism operating automatically to interrupt the operative engagement of the tool with the shoe when the tool arrives at a predetermined point on said margin, and means for varying said point, substantially as described. 100 105
27. A machine for operating on shoes, having, in combination, a tool, a shoe support, mechanism for causing the point of operation to be transferred along the margin of the shoe sole, means for pressing the shoe and tool into operative engagement, and mechanism operating automatically to render said means inoperative when the tool arrives at a predetermined point on the margin, substantially as described. 110 115
28. A machine for operating on shoes, having, in combination, a tool, a shoe support, mechanism for causing the point of operation to be transferred along the margin of the shoe sole, means for pressing the shoe and tool into operative engagement, mechanism operating automatically to render said means inoperative when the tool arrives at a predetermined point on the margin, and means for varying said point, substantially as described. 120 125
29. A machine for operating on shoes, having, in combination, a tool, a shoe support, mechanism for causing the point of opera- 1

tion to be transferred along the margin of the shoe sole, and mechanism operating automatically when the tool arrives at a predetermined point on the margin to separate the shoe and tool, substantially as described.

30. A machine for operating on shoes, having, in combination, a tool, a shoe support, mechanism for causing the point of operation to be transferred along the margin of the shoe sole, mechanism operating automatically when the tool arrives at a predetermined point on the margin to separate the shoe and tool, and means for varying said point, substantially as described.

15 31. A machine for operating on shoes, having, in combination, a tool, a shoe support, mechanism for causing the point of operation to be transferred along the margin of the shoe sole, and mechanism acting automatically when the tool arrives at the juncture of the shank and forepart to interrupt the operative engagement of the tool with the shoe, substantially as described.

32. A machine for operating on shoes, having, in combination, a tool, a shoe support, mechanism for causing the point of operation to be transferred along the margin of the shoe sole, mechanism acting automatically when the tool arrives at the juncture of the shank and forepart to interrupt the operative engagement of the tool with the shoe, and means for adjusting said mechanism for shoes of different styles, substantially as described.

35 33. A machine for operating on shoes, having, in combination, a tool, a shoe support, mechanism for causing the point of operation to be transferred along the margin of the shoe sole, and mechanism acting automatically when the tool arrives at the juncture of the shank and forepart to separate the shoe and tool, substantially as described.

34. A machine for operating on shoes, having, in combination, a shoe support, a tool support, a plurality of tools carried by the tool support, mechanism for causing the point of operation to be transferred along the shoe, and mechanism for shifting the tools to bring them successively into operative relation to the shoe, substantially as described.

35. A machine for operating on shoes, having, in combination, a shoe support, a tool support, a plurality of tools carried by the tool support, mechanism for causing the point of operation to be transferred along

the shoe, mechanism for separating the shoe and tools, and mechanism for shifting the tools to move one out of and another into operative relation to the shoe, substantially as described.

36. A machine for operating on shoe soles, having, in combination, two tools for operating along the opposite sides of a shoe sole, mechanism for causing the points of operation to be transferred along the opposite margins of the sole, and mechanism acting to bring each tool into operation when a predetermined point on its side of the shoe is reached, substantially as described.

37. A machine for operating on shoe soles, having, in combination, two tools for operating along the opposite sides of a shoe sole, mechanism for causing the points of operation to be transferred along the opposite margins of the sole, mechanism acting to bring each tool into operation when a predetermined point on its side of the shoe is reached and means for adjusting the mechanism to independently vary the points on opposite sides for different styles of shoes, substantially as described.

38. A machine for operating on shoes, having, in combination, a support for a shoe, an edge setting tool, mechanism for actuating the tool and for causing the point of operation to be transferred along the edge of the shoe sole, and mechanism operating automatically to interrupt the operative engagement of the edge setting tool with the edge of the sole when the tool arrives at a predetermined point on the sole, substantially as described.

39. A machine for operating on shoes, having, in combination, a support for a shoe, an edge setting tool, mechanism for actuating the tool and for causing the point of operation to be transferred along the edge of the shoe sole, and mechanism acting automatically when the tool arrives at the juncture of the shank and forepart to interrupt the operative engagement of the tool with the edge of the sole, substantially as described.

In testimony whereof we affix our signatures, in presence of two witnesses.

ERASTUS E. WINKLEY.
BENJAMIN PHILLIPS.
